MULTIPLE STAGE REFRIGERATION

Burdell S. Williams, Oakwood, Ohio, assignor to
 Chrysler Corporation, Highland Park, Mich., a
 corporation of Delaware

Application March 21, 1946, Serial No. 656,009

2 Claims. (Cl. 62—115)

1

My present invention relates to cascade refrigeration and has for its principal object to achieve abnormally low temperatures, such as in compartments where articles may be tested at arctic or sub-arctic temperatures. The invention has particular utility in connection with the testing of parts for use in airplanes intended to operate in the stratosphere, but many other utilities will be apparent to manufacturers or users of manufactured goods. A further purpose for which the invention is applicable is in the quick freezing of food stuffs. The ultimate uses of the invention are wide and varied and form no limitation of the scope of my invention.

A further object of my invention is to provide low temperature refrigeration by the use of a plurality of condensing units of the compressor-condenser type, connected in series whereby a high stage condensing unit employing a first separate volume of volatile refrigerant is used to condense a second separate volume of refrigerant in an intermediate stage condensing unit, which in turn is used to condense a third separate volume of refrigerant in a low stage condensing unit, which third volume of refrigerant is used to perform the actual work of refrigeration. By the use of my system I avoid complicated and expensive multiple stage compressors or condensers.

A further object of my invention is the solution of the problem of achieving low temperature by the use of ordinary refrigerants in an economical and efficient manner. It is well known that certain refrigerants provide economical operation when condensed at normal temperatures such as provided by average city water, whereas the same refrigerant would be very uneconomical or impractical at lower temperatures. By cooling one body of volatile refrigerant of one type by the use of city water and employing this refrigerant to cool a second body of a second type of refrigerant I am able to achieve abnormally low temperatures in a highly efficient manner.

These and other objects and advantages of my invention will be apparent from the following specification taken in connection with the accompanying drawing.

In the drawings the figure is a schematic representation of the refrigeration system.

Referring to the figure there is disclosed a high stage condensing unit 10, an intermediate stage condensing unit 11 and a low stage condensing unit 12. Each of these units comprises an electrically driven hermetically sealed compressor, a suitable form of which is illustrated and claimed in the patent to Neeson, No. 2,247,449 of July 1,

1941, and a condenser such as disclosed in the patent to Jewell, No. 2,149,737 of March 7, 1939. Other types of compressors and condensers may be used without departing from the spirit of my invention.

A body of refrigerant is compressed and condensed by the condensing unit 10, the compressed refrigerant being discharged into the shell of a condenser 13 through which passes a tube carrying water from a source of supply under control of a valve 4. The water, after cooling the refrigerant, passes through a compressor lubricant cooling coil 14 in the high stage compressor, then through a compressor lubricant cooling coil 15 in the intermediate stage compressor, and is then discharged to a drain or the like. A suitable form of compressor cooling coil is disclosed in the patent to Simons, No. 2,192,654 of March 5, 1940. The liquid refrigerant condensed in shell 13 passes through a hand valve 16, strainer 17, expansion valve 19 under control of a superheat bulb 2 reflecting the temperature of the suction to the high stage compressor, coils in series in the condenser shell 20 of the intermediate stage condensing unit 11, compressor cooling coil 21 in the low stage compressor, and back to the suction inlet of the high stage compressor. Thus, the body of refrigerant employed in the first condensing unit is expanded to cool the refrigerant in the second condensing unit and the compressor of the third condensing unit.

Gas which is compressed by the intermediate stage compressor is condensed in the shell 20 and passes through a hand valve 25, strainer 26, expansion valve 28 controlled by a superheat bulb 29 on the suction inlet to the intermediate stage compressor, coils in series in the condenser shell 30 of the low stage condensing unit and back to the intermediate stage compressor. A separate body of refrigerant is thus passed through a refrigeration cycle to cool the condenser of the low stage condensing unit.

Gas which is compressed in the compressor of the low stage condensing unit 12 is cooled and liquefied in the shell 30 and passes through hand valve 31 to a discharge pipe 32. Pipe 32 has a branch containing the usual expansion valve 33 which permits variable amounts of refrigerant to pass to liquid pipes 34 and 35 in parallel. Pipe 34 leads to expansion coils 36 and 37 in series and pipe 35 leads to expansion coils 38 and 39 in series. The coils 36, 37, 38 and 39 may be arranged against the four walls, respectively 40, 41, 42 and 43, of a first cooling compartment, but 56 may obviously be arranged in desired manner.

in separate compartments, or together or otherwise separated for various purposes. Coils 36 and 37 lead to branch suction pipe 44, and coils 38 and 39 lead to branch suction pipe 45, which are joined to suction pipe 46 having a manual valve 47 therein and which leads to a tank 48 from which the suction pipe of the low stage compressor extends. The tank 48 provides means to insure against passage of liquid into the compressing unit. A superheat bulb 50 is attached to the pipe 46 at the outlet side of valve 47 and is connected to the expansion valve 33 to regulate the volume of refrigerant passed therethrough in accordance with known principles.

Liquid pipe 32 contains an expansion valve 51 feeding controlled amounts of refrigerant to branch pipes 52 and 53. Pipe 52 leads to expansion coils 54 and 55 in series, and pipe 53 leads to expansion coils 56 and 57 in series. Coils 54, 55, 56 and 57 may be arranged along the walls 58, 59, 60 and 61 of a second cooling compartment or otherwise arranged as described with the first set of expansion coils. Coils 53 and 57 are connected to pipe 62, and coils 54 and 55 to pipe 63, which are joined to branch suction pipe 64. The pipe 64 has therein a manually set valve 65 and returns to the tank 48 from which the expanded gas re-enters the low stage compressor. A superheat bulb 66 attached to pipe 64 controls valve 51 in accordance with known principles.

The cooling effect in each compartment will be under control of the setting of valves 47 and 65 which may be balanced one against the other to permit lesser flow of refrigerant to one than to the other, or all to one and none to the other, or equal flow if equal temperatures in the two compartments are desired. As permitted by the extent of opening of valves 47 or 65, the expansion valves 33 and 51 will regulate the flow to the expansion coils in accordance with the superheat setting of the valves.

It is to be appreciated that the high stage condensing unit may comprise an air cooled condenser or other suitable form of condensing means but I prefer a water cooled condenser for economy and simplicity. I prefer using dichlorodifluoromethane for the high stage refrigerating medium, dichlorodifluoromethane for the intermediate stage refrigerating medium and monochlorodifluoromethane for the low stage refrigerating medium. By the use of such refrigerants I am able to obtain economy of operation and high efficiency since each body of refrigerant is employed at temperatures and pressures for which it is most suited.

Having illustrated and described a preferred embodiment of my invention, I nevertheless claim all such modifications thereof as come within the scope of the following claims:

1. The method of achieving abnormally low temperatures through the use of a plurality of mechanical condensing units requiring lubrication, comprising passing a gaseous refrigerant 5 through a high stage cycle, employing water to condense the high stage refrigerant and to cool the lubricant of at least one condensing unit, employing the high stage refrigerant to condense the refrigerant of a succeeding condensing unit 10 and to cool the lubricant of a final low stage condensing unit, passing a second volume of gaseous refrigerant through an intermediate refrigeration cycle, employing the intermediate cycle refrigerant to condense the refrigerant of the low stage condensing unit, and employing a third volume of gaseous refrigerant in the final low-stage refrigeration cycle.

2. A cascade refrigerating system comprising a high stage condensing unit including a high stage 20 compressor and a high stage condenser, an intermediate stage condensing unit including an intermediate stage compressor, and an intermediate stage condenser, a low stage condensing unit including a low stage compressor and a low stage condenser, a water circulating system including a portion for cooling said high stage condenser and other portions for cooling said high stage and said intermediate stage compressors, a first refrigerant circulating system including said high 30 stage condensing unit and comprising an expander for cooling said intermediate stage condenser and an extension thereof for cooling said low stage compressor, a second refrigerant circulating system including said intermediate stage 35 condensing unit and comprising an expander for cooling said low stage condenser, and a third refrigerant circulating system including said low stage condensing unit and comprising expansion means for extracting heat from a space to be cooled.
